I. BRUCE

Des. 106,130

CLOCK CASE

Filed June 9, 1937

FIG. 1.

FIG. 2.

Inventor:
Ivan Bruce,
by Harry E. Dunham,
His Attorney.

UNITED STATES PATENT OFFICE

106,130

DESIGN FOR A CLOCK CASE

Ivan Bruce, Framingham, Mass., assignor to Warren Telechron Company, a corporation of Maine

Application June 9, 1937, Serial No. 69,762

Term of patent 14 years

To all whom it may concern:

Be it known that I, Ivan Bruce, a citizen of the United States, residing at 140 Union Avenue, Framingham, in the county of Middlesex, State of Massachusetts, have invented a new, original, and ornamental Design for a Clock Case, of which the following is a specification, reference being had to the accompanying drawing, forming a part thereof.

Fig. 1 is a front perspective view of a clock case showing my new design, and Fig. 2 is a side view thereof in diagrammatic outline.

I claim:

The ornamental design for a clock case as shown.

IVAN BRUCE.
